UNITED STATES PATENT OFFICE.

ALBERT C. SCHULZ, OF BRIDGEPORT, CONNECTICUT, ASSIGNOR TO THE LOCOMOBILE COMPANY OF AMERICA, OF NEW YORK, N. Y., A CORPORATION OF WEST VIRGINIA.

DUMPING AND REMOVABLE BODY.

1,243,635.

Specification of Letters Patent. Patented Oct. 16, 1917.

Application filed November 25, 1912. Serial No. 733,277

To all whom it may concern:

Be it known that I, ALBERT C. SCHULZ, a citizen of the United States, and a resident of Bridgeport, county of Fairfield, State of Connecticut, have invented an Improvement in Dumping and Removable Bodies, of which the following description, in connection with the accompanying drawings, is a specification, like characters on the drawings representing like parts.

This invention relates to loading and unloading apparatus, and more especially, though not exclusively, to dumping and removable bodies for trucks, more particularly motor trucks.

My invention will be best understood by reference to the following specification, when taken in connection with the accompanying illustration of one specific embodiment thereof, while its scope will be more particularly pointed out in the appended claims.

In the drawings:

Figure 1 is a side elevation of a motor truck embodying my invention;

Fig. 2 is a side elevation of a motor truck showing the body in its dumping position;

Fig. 3 is a plan of a portion of the truck with the body removed;

Fig. 4 is a plan of a portion of the truck with the body removed;

Fig. 5 is a longitudinal section on line 5—5 of Fig. 3;

Fig. 6 is a sectional view on line 6—6 of Fig. 5;

Fig. 7 is a longitudinal section on line 7—7 of Fig. 4;

Fig. 8 is a sectional view on line 8—8 of Fig. 7;

Fig. 9 is a plan section on line 9—9 of Fig. 7;

Fig. 10 is a rear elevation of the truck;

Fig. 11 is an enlarged section on line 11—11 of Fig. 3;

Fig. 12 is an enlarged longitudinal sectional view illustrating the link hook about to disengage from the trunnions of the feed-nut;

Fig. 13 is a diagrammatic view illustrating the removal of the body onto the unloading platform; and

Fig. 14 is a diagrammatic view illustrating the replacement of the body on the truck frame.

Referring to the drawings, and to the em-

bodiment of my invention which I have selected for illustrative purposes, I have there shown a motor truck having a frame, herein comprising a pair of side members 1—1, tied together by cross members 2, 3, 4 and 5. This frame supports a guideway to sustain the body, said guideway being herein in the form of a track comprising two rails 6—6, which may be in the form of channel members having upturned flanges forming guides for the body wheels which will be presently described.

Mounted in any suitable manner upon this track is a body 7, which may be and preferably is provided with a plurality of pairs of wheels 8—8, 9—9, 10—10, and 11—11, journaled in suitable bearing brackets 12—12, 13—13, 14—14 and 15—15, secured to the body. These wheels are arranged to travel upon the channel rails 6—6, and are guided by the upturned flanges of the latter. A pair of supporting arms 16—16 secured to the frame constitute in effect continuations of the rails 6 of the guideway. These arms may be provided with downwardly inclined portions 17—17, and upwardly rising portions 18—18, forming wheel-receiving depressions 19—19, the latter being intended to receive the wheels 9—9 during the dumping operation as will presently appear. The supporting arms may be provided at their rearward extremities with downwardly and rearwardly inclined portions 20—20, for a purpose which will appear hereafter. The arms are preferably provided with rearwardly diverging upturned flanges 21—21, which will serve as guides for the body wheels and when the body is being replaced upon the truck frame, if there is any misalignment between the body and truck frame, the flanges on one side or the other will serve to guide the wheels and compel them to roll into their proper places upon the rails 6—6.

As a means for preventing the body wheels from being lifted off of the rails 6—6, there may be provided suitable means on the frame engaging with a part carried by the body, as for example, a pair of brackets 22—22, secured to the side members 1—1, and having inwardly projecting lugs or flanges 23—23, beneath which are located pins 24—24 carried by the brackets 13—13 respectively. Preferably, the lugs or flanges 23 are inclined downwardly toward the

front of the vehicle, so that when the body is brought forward into its normal position, the downward inclination of the flanges will act through the pins 24 to cause the wheels 5 to be drawn down firmly against their rails, thus firmly holding the body in its normal position.

The truck may be provided with any suitable driving means, but herein has a motor, 10 or engine, 25, which drives the truck through suitable mechanism, including a main clutch 26 of common form, a shaft 27 and transmission mechanism including a pinion 28, secured to the shaft 27, and permanently meshing 15 with and driving a gear 29 secured to a counter-shaft 30. Arranged in line with the shaft 27, is a main shaft 31, having thereon a pair of sliding gears 32 and 33, the former being adapted to be meshed with a gear 34, 20 secured to the counter-shaft 30, and the other being adapted to be meshed with a second gear 35, also secured to the counter-shaft. The gearing thus briefly described forms simply a part of a common form of 25 transmission gearing which is utilized in a well known manner to provide a series of different ratios between the engine and driving wheels. The sliding gears 32 and 33 are shown in Fig. 4 in what is commonly 30 known as neutral position, and when these gears are in this position, and the main clutch 26 is engaged, the counter-shaft 30 will be driven by the gears 28 and 29. It will be unnecessary to further describe the 35 driving mechanism of the truck, since it will be similar in its general features to common forms of motor vehicles.

I will now describe the mechanism by which the power of the truck driving engine 40 or motor is utilized to dump the load or remove the body from the truck frame and replace the same thereon at will. Journaled in suitable bearings 36 and 37 on the cross members 2 and 5, respectively, is a feed- 45 screw 38 having thereon a feed-nut 39 (Figs. 3, 11 and 12). The feed-nut may be provided with vertical trunnions 40—40, mounted in a yoke formed in two parts 41—41 secured together about the trunnions 40 by 50 bolts 42. As a means for preventing the nut from rotating about its axis, this yoke is provided with laterally projecting trunnions 43—43, on which are journaled rollers 44—44, arranged to travel in a pair of 55 guides 45—45, herein formed by pairs of angle irons 46—46 secured to angle irons 47—47, the latter being mounted upon the cross members 2, 3 and 4 of the frame. By this means, the nut is held against rotation, 60 and the rotation of the screw is utilized to move the nut longitudinally for the purpose which will presently appear.

The nut 39 may be connected to the body 7 by any suitable means, but herein there is 65 provided a link 48 forked at its forward end

to provide a pair of hooks 49 (see Figs. 3 and 12), normally straddling the feed-nut 39, and engaging the trunnions 43. This provides a driving connection which may be disconnected at will, when it is desired to 70 remove the body from the frame of the truck. The rear end of the link 48 is connected to the body preferably by a universal connection, herein comprising a stud 50 secured to the body and having pivoted 75 thereon a block 51 provided with trunnions in the form of studs 52—52 pivoted in a fork 53 at the rear end of the link 48. By the described connections, the body link 48 is universally connected to the body as well 80 as to the feed-nut, so that in remounting the body on the truck frame, the body and frame may be out of line, and the link 48 can still be engaged with the trunnions 43 of the feed-nut 39. 85

It will now be evident that by rotating the feed-screw in the proper direction, it will act through the feed-nut and body link to move the body rearwardly or forwardly along the frame. It will also be evident that 90 when the feed-screw is not rotated, the described connections will serve as a means for locking the body against longitudinal movement.

The feed-screw may be driven by the 95 motor by any suitable mechanism, but herein it is driven by mechanism connecting the feed-screw with the countershaft 30. Preferably this mechanism affords a means of connecting the feed-screw with, and disconnecting the same from the countershaft and driving the feed-screw in either direction at will. Herein the feed-screw is provided at its forward end with a sprocket wheel 54 connected by a chain 55 to a sprocket wheel 105 56, the latter being secured to a shaft 57 journaled in suitable bearings 58 and 59 in a gear case or housing 60. 100

Mounted loosely upon this shaft is a spur gear 61 and a sprocket wheel 62. The 110 spur gear 61 meshes with a spur gear 63 secured to a shaft 64, journaled in suitable bearings 65 and 66, in the gear case 60. A sprocket wheel 67 also secured to this shaft is connected to the sprocket wheel 62 by a 115 chain 68. The shaft 64 may be connected to the transmission countershaft 30 by any suitable means, but herein the transmission mechanism is provided with a gear case or housing 69, having an extension 70 forming 120 a casing for a clutch 71, which may be utilized at will to connect the transmission counter-shaft 30 with, and disconnect the same from the shaft 64. The clutch 71 herein comprises a member 72 secured to the 125 counter-shaft 30, and a clutch member 73 slidably, but non-rotatably mounted on the forward end of a shaft 74, the latter being journaled in a suitable bearing 75 in the casing 70, and being coupled to the shaft 64 130.

by a suitable coupling 76. The clutch 71 may be of any suitable type, but herein the members 72 and 73 are provided with suitable inter-engaging jaws, or lugs 77 and 78 of common form.

The clutch member 73 may be shifted into and out of engagement with the clutch member 72 by any suitable means, but herein is provided with a circumferential groove 79, 10 which receives a yoke 80, having trunnions 81 pivoted in a forked clutch shifting arm 82 of common form, the latter being secured to a rock-shaft 83 mounted in suitable bearings in the casing 70. Secured to the shaft 15 83 is a lever 84, connected by a link 85 to one arm 86 of a bell-crank lever 87, the other arm 88 of which is connected by a link 89 to a lever 90, secured to a shaft 91.

In order that the feed-screw may be driven 20 in either direction at will, the gear 61 or the sprocket wheel 62 may be secured to the shaft 57 by any suitable form of clutch 92, herein comprising a shiftable member 93, slidably but non-rotatably mounted upon the shaft 57, and having two sets of suitable teeth or jaws 94 and 95, adapted to be engaged respectively with corresponding sets of teeth or jaws 96 and 97, constituting clutch members on the gears 62 and 61 respectively. The clutch member 92 may be shifted by any suitable means, but is herein provided with a circumferential groove 98, in which is located a yoke 99 having trunnions 100 pivoted in a forked clutch shifting lever 101, secured to a rock-shaft 102 journaled in suitable bearings in the casing 60. Secured to the rock-shaft 102 is a lever 103, connected by a link 104 to a lever 105, which latter is secured to a sleeve 106 encircling the shaft 91.

The shaft 91 is mounted to rock in suitable bearings 107 and 108, while the sleeve 106 is mounted to rock in a bearing 109, the latter bearing being formed in a bearing bracket 110 mounted on the side member 1 of the frame adjacent the driver's seat (see Figs. 7 and 8). Keyed to the shaft 91 is a lever 111, and keyed to the sleeve 106 is a similar lever 112, between which levers is interposed a manually operable lever 113 pivoted at 114 on a block 115 swiveled on the shaft 91. This manually operable lever is engaged on opposite sides as shown in Fig. 8 by two springs 116 and 117 secured to the levers 111 and 112 respectively. The levers 111 and 112 are provided with opposed notches 118 and 119, respectively, either of which notches is adapted to receive the lever 113 when the latter is rocked to one side or the other about the pivot 114. It will now be evident that by rocking the lever 113 toward the right (Fig. 8), said lever will be coupled to the lever 112, and the manually operable lever 113 may be thus utilized to shift the clutch member 93, by simply rocking the lever 113 for-

ward or backward, as may be required. Now if, on the other hand, it be desired to utilize the manually operable lever 113, to shift the clutch member 73, the manually operable lever is first swung toward the left (Fig. 8), into the notch 118 and thus, being coupled to the lever 111, may then be swung on the axis of the shaft 91, and will thus act through the described connections to engage or disengage the clutch 71 at will.

As a means for providing a selective control of the clutches 71 and 92, I may provide a plate 120, commonly known as a gate, provided with two longitudinal slots 121 and 122, connected by a transverse slot 123. The hand lever 113 normally stands in the middle of the slot 123 out of engagement with the forked levers 111 and 112. To disengage the clutch 71, the hand lever 113 is first moved laterally from the slot 123 into the slot 121, and is then moved forwardly (toward the right, Fig. 9) to the end of the slot 121. If, on the other hand, the operator wishes to engage the clutch 92, he moves the hand lever 113 laterally from the slot 123 into the slot 122. With the hand lever in the slot 122, a forward movement of the lever to the front end of the slot will result in shifting the clutch 92 to cause forward movement of the body, while movement of the lever to the rear end of the slot 92 will cause a reverse movement of the body. The hand lever may be held in various positions of adjustment by spring-pressed pins 124 and 125, carried by the forked levers 111 and 112, and engaging suitable depressions formed in the side of the plate 120.

It will now be evident that the operator, by first placing the gears 32 and 33 in their neutral position (see Fig. 4), by the use of the usual transmission gear shifting lever (not shown), and then shifting the hand lever 113 in the described manner, may utilize the power of the engine to cause the feed-screw to be rotated in either direction, or to be stopped at will.

I will now describe the devices by which the rearward movement of the body, under the influence of the described connection, is utilized to enforce a tilting, or dumping movement. It will be readily apparent that if, after the body has been moved rearwardly until the wheels 9-9 enter the wheel-receiving depressions 19-19, some means is provided for preventing further rearward movement of the body, continued movement of the feed-nut and the body link will result in a tilting or dumping action, (see Fig. 2). As a means for limiting such rearward movement of the body to enforce a tilting action, there may be provided a pair of stops 126-126, mounted on pivots 127-127 on the arms 16-16, which form the rearward extensions of the rails 6-6. These stops are herein in the form of hooks,

which may be held raised in the position shown in Figs. 1 and 5 by latches, or dogs, 128, secured to a rock-shaft 129 mounted to rock in suitable bearings provided in the arms 16. Stops 130 serve to limit the swinging movement of the latches or dogs 128 toward the right (Fig. 5), while stops 131 serve to limit swinging movement of said dogs toward the left. The stops 126 are adapted to receive trunnions 132 carried by the body 7 concentric with the wheels 9, and held in the brackets 13. In fact, these trunnions may constitute shafts for the wheel 9, and may have formed on their outer ends the pins 24 hereinbefore referred to. When the body is moved rearwardly and the wheels 9 roll down the incline 17 into the depressions 19, the trunnions 132 engage cam surfaces 133 formed on the stops 126, and lift the latter to a sufficient extent to allow the trunnions to pass into trunnion-receiving slots 134, whereupon the stops will drop, and will thus interlock with the trunnions and securely hold the latter, so that continued movement of the feed-nut and body link toward the rear will result in a tilting movement of the body from the position shown in dotted lines in Fig. 2 to the position shown in full lines therein, thus dumping the load.

The body may be, and preferably is, provided with a tail-board 135, having secured thereto a pair of arms 136 pivoted at 137. With this arrangement of the tail-board, in dumping bricks, rocks, or any other material in which the lower edge of the tail-board is liable to catch before the body reaches the maximum dumping angle, the tail-board will lift about its pivots, and no undue strain will be brought upon these parts. The board may be normally locked in its closed position by a pair of latches 138—138, in the form of well-known engaging pins 139—139 on the tail-board, these latches being secured to a rock-shaft 140, mounted in bearings upon the body. The latch 138, upon one side of the body (see Fig. 1) is provided with an arm 141, through which passes a rod 142, having secured thereto a collar 143, serving as an abutment for the arm 141, against which abutment said arm is normally held by a coiled spring 144, bearing at its opposite end against a collar 145, secured to said rod. The rod 142 may be actuated by any suitable means to cause the same to release the tail-board at the moment of dumping, but herein the forward end of the rod is pivoted to an arm 146, secured to a rock-shaft 147 journaled in a bearing bracket 148, and having secured thereto a tripping arm 149 adapted to engage the cam surface 133 of one of the stops 126 (Fig. 2). When this occurs, which will be just before the position shown in Fig. 2 is reached, the tail-board will be released

and allowed to swing open, and the out-flowing material from the body will naturally swing the tail-board rearwardly and out of the way of the discharging material.

When the full dumping position has been reached, the operator may stop the rotation of the feed-screw and reverse the same by the use of the hand-lever 113, but if desired, this action may take place automatically, through mechanism which I will now describe. Connecting the arms 16 is a rod 150, upon which a sleeve 151 is mounted for rocking movement. To this sleeve is secured a bell-crank lever 152, carrying a body-engaging member 153, which may be adjustably mounted therein, to determine the point at which the disengagement of the clutch 92 will take place. The bell-crank lever 152 is connected by a link 154 to a lever 155, pivoted at 156 on one of the angle irons 47 (see Figs. 3 and 5). A second link 157 also pivoted to the lever 155 extends forward and is pivoted to a lever 158 secured to a rock-shaft 159 mounted in suitable bearings 160 on the side of the angle irons 47. Secured to the rock-shaft 159 is a lever 161 connected by a link 162 to the lever 103 hereinbefore referred to. It will be remembered that the lever 103 operates to shift the reversing clutch 92. It will now be evident that when the body reaches a certain predetermined point in its tilting movement, its bottom will engage the member 153, and will act through the connections just described to shift the member 93, and stop the movement of the feed-screw. The body may now be caused to return to its normal position, under the power of the engine, by utilizing the hand-lever 113 to shift the clutch member 93 into engagement with the clutch member 97, whereupon the feed-screw will rotate in the reverse direction. When the body starts to return toward its normal position, the closing of the tail-board is insured by the pivot 137 being located forward of the plane of the tail-board, and the center of gravity of the tail-board being consequently located in the plane at the rear of said pivot. Toward the end of the closing movement of the tail-board, the pins 139 will engage the inclined rear ends of the latches 138, and lift the latter against the tension of the springs 144, which are provided for this purpose, and the latches will snap down upon the pins 139, thereby securely holding the tail-board closed.

If desired, the hook-shaped stops 126 may be provided with spring-pressed pins 163—163, to prevent said stops from leaving the dogs or latches 128, when the truck is traveling over rough roads.

When the stops 126 are in their raised position, the spring-pressed pins 163 may engage bosses 164 provided with depressions 165 to receive the pins, and when the stops 130

are in their lowered position, the spring-pressed pins may enter depressions 166 provided in the bosses or stops 131, hereinbefore referred to.

5 In order that a truck may be kept in use as continuously as possible, with the minimum amount of time for loading and unloading, it is desirable to provide more than one body for a given truck, so that when the 10 truck is hauling a load in one body from one point to another, another body may be loaded with materials, and the second body substituted for the first body in a few moments, when the truck has returned with the 15 previously unloaded body. In order that this may be accomplished quickly and conveniently, I have provided a body which is not only adapted to dump its load under the power of the engine, but which is also so 20 constructed that the body may be entirely removed from the truck, and replaced thereon under the power of the engine.

Referring now to Figs. 12, 13 and 14, the 25 operation of removing and replacing the body will be described. When it is desired to remove the body, the truck is backed up to an unloading platform of suitable height, exemplified by the platform 167. The dogs 128 are then rocked into the position illustrated in Figs. 13 and 14, and the stops 126 are lowered into the positions shown in said figures, so as to be entirely out of the path of the trunnions 132. The operator then 30 brings the power of the engine into play, in the manner hereinbefore described, to cause the body to be moved, under the power of the engine, rearwardly along the truck frame, and the body will be delivered upon the unloading platform 167 in the manner 35 illustrated in Fig. 13, first the pair of wheels 8 resting upon the platform, and then the remaining wheels in succession passing through the truck frame onto the platform in an obvious manner. When this has taken 40 place, the hook 49 of the body link 48 will be automatically disengaged from the trunnions 43 (see Fig. 12) by engaging a pair of inclined surfaces 168 which will lift the hook and free it from the trunnions in an 45 obvious manner, the opening in the hook being somewhat elongated for the purpose of facilitating the disengagement. At this moment, one of the rollers 44 carried by the 50 feed-nut 39 engages the lever 155, and acts through the links 157, lever 158, rock-shaft 159, lever 161, and link 162, to rock the lever 163, thus causing the reversing clutch to be 55 disengaged, whereupon the movement of the feed-screw and nut will cease.

60 Now, assuming that it is desired to replace the body, or place another body upon the truck, the selected body is first brought into position upon the loading and unloading platform substantially in line with the 65 truck, and the hook 49 of the body link 48

is hooked upon the trunnions 43, the feed-nut for that purpose being advanced along the feed-screw slightly. The power of the engine is then applied to rotate the feed-screw in the proper direction to cause the feed-nut to advance toward the front of the 70 truck, with the result that the body is hauled onto the truck.

The wheels 11 will first engage the inclined surface 20 as illustrated diagrammatically in Fig. 14, and will then ride up onto the inclined surface 17. The wheels 10, 9 and 8, will then follow along in order, it being evident that as the loaded body advances along the truck frame, the latter will 75 gradually sink upon its springs and will approach the level of the loading and unloading platform. When the body reaches its normal position upon the truck frame, one of the rollers 44 carried by the feed-nut 39 will engage a lever 169, connected by a link 170 to the lever 158, and will act 80 through these connections, and through the connections hereinbefore described, to disengage the reversing clutch, and thus cause the 85 rotation of the feed-screw to cease, whereupon the body will stop. It will be understood, however, that if desired, the automatic operation may be dispensed with, and the stopping and starting of the feed-screw 90 may be accomplished by the use of the hand lever, in the manner hereinbefore described.

95 While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made without departing from the principles thereof.

100 Having thus described one embodiment of my invention, what I claim and desire by Letters Patent to procure is:

1. In a vehicle, the combination of a 105 guideway having downwardly inclined rear portions and upwardly rising portions forming wheel-receiving depressions, said downwardly inclined and upwardly rising portions being provided with lateral guide walls and a body having wheels supported on said 110 guideway.

2. An apparatus of the class described comprising, in combination, a track, a body having wheels supported on said track, said track having a depression adjacent one end adapted to receive a pair of said wheels, pivots concentric with the wheels of said pair, stops aligned with said depressions and adapted to coöperate with said pivots.

3. An apparatus of the class described 120

comprising, in combination, a track, a body having wheels supported on said track, guides disposed adjacent said track and having grooves opening toward the same; a pair of said wheels having axles extending laterally to engage in said grooves and to form trunnions; stops disposed adjacent one end of the track and adapted pivotally to engage said trunnions and means for moving said body along said track.

4. An apparatus of the class described comprising, in combination, a guideway, a body mounted to move longitudinally of said guideway, a trunnion carried by said body, and a stop mounted to move into and out of the path of said trunnion, said stop being provided with means co-operating with said trunnion to move said stop into inter-engagement with said trunnion.
5. An apparatus of the class described having, in combination, a guideway, a body mounted to move longitudinally of said guideway, pivot means carried by said body, a pair of stops mounted to move up and down into and out of the path of said pivot means, and means to cause said stops to be automatically lifted and allowed to drop into interlocking engagement with said pivot means.
6. An apparatus of the class described having, in combination, a guideway, a body mounted to move longitudinally of said guideway, pivot means carried by said body, and a pair of stops mounted to move into and out of the path of said pivot means, said stops having provision to interlock with said

pivot means and hold the latter against forward and rearward movement.

7. An apparatus of the class described having, in combination, a guideway, a body mounted to move longitudinally of said guideway, pivot means carried by said body, a pair of stops mounted to move into and out of the path of said pivot means, and means carried by said stops to cause said pivot means to interlock with said stops and hold the latter against forward and rearward movement.

8. An apparatus of the class described, having, in combination, a guideway, a body mounted to move longitudinally of said guideway, pivot means carried by said body, a pair of stops mounted to move into and out of the path of said pivot means, and cams on said stops to co-operate with said pivot means to move said stops and cause them to interlock with said pivot means.

9. In a vehicle, the combination of a guideway having terminal portions forming wheel-receiving depressions, a tilting body having pivot means, wheels upon which said body is mounted to travel on said guideway, and means to cause said wheels to be locked in said wheel-receiving depressions.

In testimony whereof, I have signed my name to this specification in the presence of two subscribing witnesses.

ALBERT C. SCHULZ.
